UNITED STATES PATENT OFFICE.

ISAAC S. WOODWARD, OF WICHITA, KANSAS.

SEESAW AND ROTARY SWING.

No. 879,937.

Specification of Letters Patent.

Patented Feb. 25, 1908.

Application filed October 8, 1906. Serial No. 337,959.

To all whom it may concern:

Be it known that I, ISAAC S. WOODWARD, a resident of Wichita, in the county of Sedgwick and State of Kansas, have invented 5 certain new and useful Improvements in Seesaw and Rotary Swings; and I do hereby declare the following to be a full, clear, and exact description of the invention, such as will enable others skilled in the art to which 10 it appertains to make and use the same.

My invention relates to see-saw and rotary swing.

The object is to produce a simple inexpensive and durable machine eliminating all 15 dangerous features.

To the accomplishment of these objects and others subordinate thereto, the preferred embodiment of my invention comprehends the construction and arrangements of parts to 20 be hereinafter described, illustrated in the accompanying drawings and succinctly defined in the appended claims.

In the drawings Figure 1, is a perspective view of a swing embodying my invention. 25 Fig. 2, a vertical section of the pedestal and swivel. Fig. 3, a toothed disk. Fig. 4, a dog. Fig. 5, the method of joining bars 2 and 2^b together.

1, designates a pedestal on which is 30 mounted a swivel and bars 2, 2^b, and 3. This pedestal is preferably cast iron and is flared out at the lower end to provide against toppling over, is circular in form and the underside thereof is provided with a recess 35 4, the top end of said pedestal is approximately the same shape as the lower end, the recess extending down further and progressively diminishing and abruptly terminating at 4^a. The top of this recess has 40 annular indents 5 and 6. These indents are for reception of ball bearings 7. I provide a cast disk 9, about one half inch thick, with a round opening 11, in the center and an annular flange 12, near the perimeter, and on 45 top of the said flange are teeth 10. A cast swivel 13, having indents on the periphery thereof which are to engage the balls 7, when placed within the pedestal 1. This swivel progressively diminishes in contour from the 50 balls down, the free end being provided with a countersink 15, which is for the reception of a ball 16. The top end of the said swivel is bifurcated to receive the bars 2, 2^b, and 3, and are pierced to receive the bolts 17, 55 and 18, on these bolts bars 2, 2^b, and 3 are

pivotal secured as seen in Fig. 1. A dog 19, is made of spring steel and has an indent 20, in one end, the other end 21, is flattened out and has a round opening 22, therein, to receive the bolt 23. These dogs are slightly 60 curved to provide resiliency under concussion. The object of the aforesaid indents is to permit the dogs to straddle the flange 12, and teeth 10. The bars 2, and 2^b, are cut away and joined together as seen at A, 65 Fig. 5. The bar 3, is somewhat longer than the combined length of bars 2, and 2^b, which is for the reception of the seats 24, which are secured to the bar by screws C. On either side of the free ends of the bars are 70 battens 25, and are pivotally secured thereto by the bolts 26, and rods 27. Holes 28, and 29, are made for the purpose of adjustment. The object of curving in the bars is to give the free end of the battens a reciprocal 75 movement which is helpful to the riders in operating the machine. The free ends of these battens are pierced for the reception of the round rods 30, which rod is for the 80 rider to hold on to. The round rods 27, serve the double purpose of pivoting the battens to the bars and the riders to rest 85 their feet upon. To the bars 2, and 2^b, are pivotally secured by means of bolts 23, dogs 19. When a rotative movement is not de- 85 sired by the riders the dogs 19, can be disengaged from the teeth 10, and made pendent from the bars.

Having described the details of construction of my machine I will now describe the 90 assembling and operation thereof.

The disk is placed on the pedestal and secured thereto by the bolts 8. A bolt 16, is dropped down in the bottom of the recess 4^a, and the bolts 7, are placed in the indents 95 5, and 6, and the swivel 13, is then placed in the pedestal as seen in Fig. 2. The bars are mounted on the swivel as hereinbefore described, the dogs bolted to the bars and placed in engagement with the teeth 10. 100 When two persons mount the machine and begin to move the free ends of the bars up and down it will be seen when the dogs engage with the teeth 10, the swing will be given a rotary movement as well as up and 105 down. By reference to Fig. 2, it will be seen the lower tier of bolts 7, and bolt 16, support the weight of the swivel the bars and the riders while the upper tiers support the swivel laterally.

Having described the construction of my machine what I claim and wish to secure by Letters Patent is:—

In a see-saw and rotary swing, a pedestal having interior recesses, a plurality of detents, in one recess, a swivel detented to register with the detents in the recess and balls to lie between the swivel and the pedestal, bars mounted in the swivel, the free ends of 10 one pair of bars converging to the adjacent bar, dogs pivotally secured to one pair of

bars said dogs having a detent in one end, an annular disk with a flange having teeth thereon, as set forth.

In testimony whereof, I have signed this 15 specification in the presence of two subscribing witnesses.

ISAAC S. WOODWARD.
